PROCESS AND COMPOSITION CONTAINING AN OXYGEN RELEASING COMPOUND AND AN ORGANIC CARBONATE

Basil Hugh Chase, Heswall, England, assignor to Lever Brothers Company, New York, N.Y., a corporation of Maine

No Drawing. Filed May 3, 1963, Ser. No. 277,721
Claims priority, application Great Britain, May 7, 1962,
17,379/62

11 Claims. (Cl. 252—99)

This invention relates to processes of bleaching and to bleaching compositions; in particular it relates to processes and to compositions suitable for removing stains from textile materials.

Many detergents compositions contain an inorganic per-salt such as sodium perborate or percarbonate to provide bleaching properties. These per-salts provide a satisfactory bleach when the detergent is used at the boil, but at lower temperatures their action is rather slow. This disadvantage is becoming important with the growing use of washing machines which operate at a temperature of, for example, 50–60° C. It is an object of the present invention to provide a more effective bleach in the normal washing period at this temperature than is obtained with the per-salt alone.

Processes and compositions according to the invention also find application in the textile industry and in commercial laundering.

It has been found that improvements in bleaching can be obtained by the use of an aqueous solution containing hydrogen peroxide and an ester of carbonic acid or pyrocarbonic acid as characterised below.

It has further been found that improved bleaching compositions can be provided which contain an inorganic per-salt together with an ester of carbonic acid or pyrocarbonic acid. The esters which are suitable for use in the invention are characterised by the following per-acid formation test.

To a solution at 60° C. containing the following 500 ml. distilled water:

1.25 grams sodium pyrophosphate decahydrate

($\text{Na}_4\text{P}_2\text{O}_7 \cdot 10\text{H}_2\text{O}$)

0.154 gram sodium perborate ($\text{NaBO}_2 \cdot \text{H}_2\text{O}_2 \cdot 3\text{H}_2\text{O}$) (at 10.4% available oxygen)

is added an amount of ester, in equimolecular ratio to the available oxygen. Water soluble esters are added direct to the aqueous solution; other esters should be dissolved in 10 ml. ethyl alcohol before addition, the volume of distilled water being reduced in such cases to 490 ml. Acidic derivatives should be neutralised before addition. The mixture is mechanically stirred by means of a $\frac{3}{4}$ " glass stirrer at 600 revolutions per minute and maintained at 60° C. After one minute and after five minutes 100 ml. portions are withdrawn and immediately pipetted onto a mixture of 250 grams of cracked ice and 15 ml. of glacial acetic acid. 0.4 gram of potassium iodide is then added. The liberated iodine is immediately titrated with 0.1 N-sodium thiosulphate, using starch as indicator, until the first disappearance of the blue colour.

Esters which may be used in bleaching compositions and processes of the invention are those which give a titre of 1.0 millilitres or more in this test after one minute or after five minutes, or both.

According to the present invention there is provided a bleaching process in which is used an aqueous solution of hydrogen peroxide and an ester of carbonic acid or pyrocarbonic acid which gives a titre of not less than 1.0 millilitres of 0.1 N sodium thiosulphate in the test defined above.

2

The present invention further provides a bleaching composition which contains an inorganic per-salt together with an ester of carbonic acid or pyrocarbonic acid which gives a titre of not less than 1.0 ml. of 0.1 N sodium thiosulphate in the test defined above.

Esters which give a titre of not less than 1.0 ml. of 0.1 N sodium thiosulphate in the test defined above and hence may be used according to the invention include compounds within the class $\text{R}_1\text{O.CO.OR}_2$ in which R_1 exerts an electron attracting effect and R_2 is an alkyl, aryl, or alicyclic radical or a substituted alkyl, aryl or alicyclic radical.

The esters should not yield easily oxidisable hydrolysis products such as polyhydric phenols.

Examples of esters within the scope of the invention, that is those which give a titre of at least 1.0 ml. of 0.1 N sodium thiosulphate in the test defined above, are:

20 sodium p-sulphophenyl ethyl carbonate
sodium p-sulphophenyl methyl carbonate
sodium p-sulphophenyl phenyl carbonate
diethyl pyrocarbonate
p-carboxyphenyl ethyl carbonate
p-carboxyphenyl methyl carbonate
p-carboxyphenyl phenyl carbonate
25 o-carboxyphenyl ethyl carbonate
o-carboxyphenyl methyl carbonate
p-carboxyphenyl n-propyl carbonate
p-carboxyphenyl n-butyl carbonate
benzyl p-carboxyphenyl carbonate
30 sodium p-sulphophenyl n-propyl carbonate
sodium p-sulphophenyl n-butyl carbonate
sodium p-sulphophenyl benzyl carbonate

Hydrogen peroxide cannot, of course, be included in a solid composition, and bleaching solutions prepared from hydrogen peroxide should be prepared as required for use. The hydrogen peroxide may be added to the solution as such, or may be liberated in situ from a per-salt.

By "inorganic per-salt" is meant a salt which will give rise to hydrogen peroxide in aqueous solution. Suitable compounds are alkali metal perborates, percarbonates, perpyrophosphates and persilicates. These are believed not to be true per-salts in the strict chemical sense but to contain hydrogen peroxide of crystallisation, which is liberated in aqueous solution.

The invention can be applied to bleaching baths such as are used for treating textiles, to wash liquors, such as are used in commercial laundering and to solid bleaching compositions. Solid bleaching compositions may contain, in addition to a per-salt and an ester according to the invention, inert salts, alkaline agents and a small proportion of detergent. The invention may further be applied to detergent compositions, which contain an organic detergent, which may be soap or an organic soapless detergent. Suitable organic soapless detergents are the alkyl-aryl sulphonates, alkyl sulphates and the salts of esters or ethers of isethionic acid. Compositions according to the invention should preferably contain one or more alkaline substances in amounts such that similar compositions not containing esters would give a pH value within the range 9–11 when dissolved at the desired bleaching concentration. Most common detergent compositions contain alkaline material sufficient for this purpose. Suitable alkaline materials are, for instance, soap, alkali-metal carbonates, phosphates (including orthophosphates and water-soluble condensed phosphates, such as tripolyphosphates and pyrophosphates) and silicates.

When the invention is applied to bleaching or wash liquors, alkali sufficient to give an initial pH of 9–11 is preferably present in the bleaching or wash liquor before addition of the ester.

Compositions according to the invention may contain

any of the conventional adjuncts present in detergent compositions. There may be mentioned, supplementary builders, inert and organic materials such as alkali metal sulphates, chlorides, carboxymethylcellulose and fluorescent agents.

Compositions according to the invention must not contain water in an amount sufficient to permit appreciable chemical reaction between the components prior to use.

The proportions of per-salt and ester which may be present in compositions according to the invention will depend on the time and temperature of bleaching, the degree of bleaching required, the concentration of the bleaching solution and the individual ester and per-salt used. Under most conditions, these proportions should be such as to give a per-salt concentration in solution equivalent to 0.001 to 0.1% available oxygen.

Having regard to these factors, bleaching effects may be obtained with compositions according to the invention containing widely varying ratios of per-salt to ester. It is convenient to measure the activity of the per-salt in terms of available oxygen. Generally ratios of from $\frac{1}{4}$ to 2 and particularly from $\frac{1}{2}$ to $1\frac{1}{2}$ molecules of ester per 1 atom of available oxygen are preferred. (In converting such ratios to ratios by weight, account must be taken of the molecular weight of the ester and the available oxygen content of the per-salt used.) In particular, it is preferred to use approximately chemically equivalent amounts of ester and per-salt.

When solutions are used which are obtained by adding hydrogen peroxide and an ester according to the invention to an alkaline bath, the preferred weight ratio is from 2 to 15 parts of ester to 1 part of hydrogen peroxide (100%) depending on the molecular weight of the ester used.

When compositions according to the invention are to be used primarily as a bleach, for instance, for addition to alkaline textile bleaching baths or wash liquors, such compositions may contain any proportion of ester and per-salt, these components being preferably present in the ratio of $\frac{1}{4}$ to 2 molecules of ester per 1 atom of available oxygen, preferably $\frac{1}{2}$ to $1\frac{1}{2}$ molecules per 1 atom of available oxygen.

When an organic detergent is present in compositions of the invention, improvements in bleaching can be obtained at normal washing concentrations. Thus, for example, using a detergent composition of the invention at a concentration of 1% in aqueous solution improvements may be obtained if amounts of as little as 1% of per-salt and 2% of ester by weight of the composition are present. In such compositions, the amount of per-salt taken should provide at least 0.1% available oxygen based on the composition. Generally, detergent compositions will contain from about 10 to about 50% by weight of organic detergent. The mixed ester/per-salt content may be as high as 70% by weight provided that these components are taken in ratios of $\frac{1}{4}$ to 2, preferably $\frac{1}{2}$ to $1\frac{1}{2}$ molecules of ester per 1 atom of available oxygen. Effective proportions of ester and per-salt in detergent compositions will lie in general within the range of 2% to 30% of ester and 1% to 75% of per-salt by weight of the composition.

Best results in bleaching according to the invention are obtained under conditions of effective agitation such as exist, for instance, in a washing machine.

The following example illustrates the invention:

Example

Bleaching solutions were prepared containing:

	Percent
Sodium dodecyl benzene sulphonate	0.054
Coconut mono-ethanolamide	0.018
Sodium tripolyphosphate	0.115
Sodium sulphate	0.045
Anhydrous alkaline sodium silicate	0.029
Sodium carboxymethylcellulose	0.004
Sodium perborate tetrahydrate	0.032

and an ester in concentration as given in the table below. The carboxylic acids were converted to their sodium salts immediately before use.

A length of cotton cloth was stained by immersion in boiling tea extract for one hour. It was then thoroughly rinsed, dried and cut into pieces whose percent reflectances were measured in a Hunter reflectometer using the blue filter. The percent reflectance of the test pieces was measured again after bleaching. The bleach obtained was expressed as the difference in the two percent readings on each test-piece.

A piece of stained cloth was immersed in each of the freshly-prepared bleaching solutions at 60° C. for 10 minutes with stirring. The cloths were then removed from the solutions, rinsed three times in distilled water, ironed and their reflectance measured. The results are given in the following table.

	Ester	Concentration of ester in solution (percent)	Increase in percent reflectance	Increase in percent reflectance in absence of ester (control)
25	Sodium p-sulphophenyl ethyl carbonate	0.054	19.1	12.6
	p-Carboxyphenyl ethyl carbonate	0.042	17.9	12.6
	p-Carboxyphenyl methyl carbonate	0.039	15.1	11.3
30	p-Carboxyphenyl phenyl carbonate	0.052	19.0	11.9
	o-Carboxyphenyl ethyl carbonate	0.042	13.6	11.3
	o-Carboxyphenyl methyl carbonate	0.039	13.6	11.3
	Diethyl pyrocarbonate	0.032	22.5	15.9
35	p-Carboxyphenyl n-propyl carbonate	0.045	20.7	15.9
	p-Carboxyphenyl n-buty1 carbonate	0.048	16.3	10.6
	Benzyl p-carboxyphenyl carbonate	0.054	16.4	10.6
40	Sodium p-sulphophenyl n-propyl carbonate	0.056	21.6	15.9
	Sodium p-sulphophenyl n-butyl carbonate	0.060	18.4	10.6
	Sodium p-sulphophenyl benzyl carbonate	0.066	17.5	10.6

The esters other than p-carboxyphenyl phenyl carbonate and diethyl pyrocarbonate can be prepared by reacting an alkyl chloroformate and a phenol.

I claim:

1. A process for bleaching textile materials comprising the step of placing the article to be bleached in an aqueous solution of hydrogen peroxide and an ester selected from the class consisting of (a) esters of carbonic acid having the formula $R_1-O-CO-O-R_2$, wherein each of R_1 and R_2 is an organic radical, R_1 exerting an electron attracting effect, and (b) diethyl pyrocarbonate, said esters having a titer in the per-acid formation test of not less than 1.0 ml. of 0.1 N $Na_2S_2O_3$, the hydrogen peroxide and ester being present in amounts sufficient to provide from about $\frac{1}{4}$ to about 2 molecules of ester per atom of available oxygen.

2. A process according to claim 1 in which said aqueous solution has an initial pH between 9 and 11.

3. A process for bleaching soiled textile material comprising the steps of placing the article to be bleached in an aqueous solution of hydrogen peroxide and an ester selected from the class consisting of (a) esters of carbonic acid having the formula $R_1-O-CO-O-R_2$, wherein each of R_1 and R_2 is an organic radical, R_1 exerting an electron attracting effect, and (b) diethyl pyrocarbonate, said esters having a titer in the per-acid formation test of not less than 1.0 ml. of 0.1 N $Na_2S_2O_3$, the hydrogen peroxide and ester being present in an amount sufficient to provide from about $\frac{1}{4}$ to about 2 molecules of ester per atom of available oxygen, allowing the said article to remain in said solution at a temperature substantially below the boiling point thereof for a normal washing period, and rinsing the article.

4. A composition for use in bleaching textile material consisting essentially of an inorganic per-salt selected from the group consisting of the alkali metal perborates, percarbonates, perpyrophosphates, and persilicates, and an ester selected from the class consisting of (a) esters of carbonic acid having the formula $R_1-O-CO-O-R_2$ wherein each of R_1 and R_2 is an organic radical, R_1 exerting an electron-attracting effect, and (b) diethyl pyrocarbonate, said esters having a titer in the per-acid formation test of not less than 1.0 ml. of 0.1 N $Na_2S_2O_3$, the hydrogen peroxide and ester being present in amounts sufficient to provide from about $\frac{1}{4}$ to about 2 molecules of ester per atom of available oxygen.

5. A composition according to claim 10 which exhibits a pH between about 9 and about 11 when placed in an aqueous solution.

6. A composition according to claim 10 wherein said ester and said inorganic per-salt are present in amounts sufficient to provide from about $\frac{1}{2}$ to about $1\frac{1}{2}$ molecules of ester per atom of available oxygen.

7. A composition for bleaching textile material which is an aqueous solution of hydrogen peroxide and an ester selected from the group consisting of (a) esters of carbonic acid having the formula $R_1-O-CO-O-R_2$ wherein each of R_1 and R_2 is an organic radical, R_1 exerting an electron-attracting effect, and (b) diethyl pyrocarbonate, said esters having a titer in the per-acid formation test of not less than 1.0 ml. of 0.1 N $Na_2S_2O_3$, the hydrogen peroxide and ester being present in amounts sufficient to provide from about $\frac{1}{4}$ to about 2 molecules of ester per atom of available oxygen.

8. A process for bleaching textile materials comprising the steps of placing the article to be bleached in an aqueous solution of hydrogen peroxide and an ester selected from the class consisting of sodium p-sulfophenyl ethyl carbonate, sodium p-sulfophenyl methyl carbonate, sodium p-sulfophenyl phenyl carbonate, diethyl pyrocarbonate, p-carboxyphenyl ethyl carbonate, p-carboxyphenyl methyl carbonate, p-carboxyphenyl phenyl carbonate, o-carboxyphenyl ethyl carbonate, o-carboxyphenyl methyl carbonate, p-carboxyphenyl n-propyl carbonate, p-carboxyphenyl n-butyl carbonate, benzyl p-carboxyphenyl carbonate, sodium p-sulfophenyl n-propyl carbonate, sodium p-sulfophenyl n-butyl carbonate and sodium p-sulfophenyl benzyl carbonate, said esters having a titer in the per-acid formation test of not less than 1.0 ml. of 0.1 N $Na_2S_2O_3$, the hydrogen peroxide and ester being present in an amount sufficient to provide from about $\frac{1}{4}$ to about 2 molecules of ester per atom of available oxygen.

9. A process according to claim 8, including the additional steps of allowing said article to remain in said solution at a temperature substantially below the boiling point thereof for a normal washing period, and thereafter rinsing said article.

10. A composition for use in bleaching textile materials consisting essentially of an inorganic per-salt selected from the group consisting of the alkali metal perborates, percarbonates, perpyrophosphates, and persilicates, and an ester selected from the class consisting of sodium p-sulfophenyl ethyl carbonate, sodium p-sulfophenyl phenyl carbonate, diethyl pyrocarbonate, p-carboxyphenyl ethyl carbonate, p-carboxyphenyl methyl carbonate, p-carboxyphenyl n-propyl carbonate, p-carboxyphenyl n-butyl carbonate, benzyl p-carboxyphenyl carbonate, sodium p-sulfophenyl n-propyl carbonate, sodium p-sulfophenyl n-butyl carbonate and sodium p-sulfophenyl benzyl carbonate, said esters having a titer in the per-acid formation test of not less than 1.0 ml. of 0.1 N $Na_2S_2O_3$, the hydrogen peroxide and ester being present in amounts sufficient to provide from about $\frac{1}{4}$ to about 2 molecules of ester per atom of available oxygen.

11. A composition for bleaching textile materials which is an aqueous solution of hydrogen peroxide and an ester selected from the group consisting of sodium p-sulfophenyl ethyl carbonate, sodium p-sulfophenyl methyl carbonate, sodium p-sulfophenyl phenyl carbonate, diethyl pyrocarbonate, p-carboxyphenyl ethyl carbonate, p-carboxyphenyl methyl carbonate, p-carboxyphenyl phenyl carbonate, o-carboxyphenyl ethyl carbonate, o-carboxyphenyl methyl carbonate, p-carboxyphenyl n-propyl carbonate, p-carboxyphenyl n-butyl carbonate, benzyl p-carboxyphenyl carbonate, sodium p-sulfophenyl n-propyl carbonate, sodium p-sulfophenyl n-butyl carbonate and sodium p-sulfophenyl benzyl carbonate, said esters having a titer in the per-acid formation test of not less than 1.0 ml. of 0.1 N $Na_2S_2O_3$, the hydrogen peroxide and ester being present in an amount sufficient to provide from about $\frac{1}{4}$ to about 2 molecules of ester per atom of available oxygen.
